EARTH MOVING DEVICE

James S. Stewart, Sidney, Ohio, assignor to The
Slusser-McLean Scraper Company, Sidney,
Ohio, a corporation of Ohio

Application December 1, 1932. Serial No. 645,270

6 Claims. (Cl. 97—73)

This invention relates to new and useful improvements in earth moving devices.

It is one of the principal objects of my invention to provide for earth moving tools, such as rippers, scrapers and the like, a simple, sturdy and efficient elevating device that is automatically controlled by the operator.

My elevating device is particularly adapted for use in rippers as an easy and efficient automatic means for raising and lowering the ripper teeth. Smooth and positive in its operation, my elevating device makes it possible for the operator easily and quickly to drop the blades into the ground and remove them therefrom.

It is another object of my invention to promote the solidity of the earth moving tool by cutting the ripper teeth out of flat high carbon steel instead of employing bar steel bent to shape for this purpose.

Other important and incidental objects will be brought out in the following specification and particularly set forth in the subjoined claims.

In the accompanying drawings illustrating my invention, Figure 1 is a side elevational view of a ripper embodying my invention, showing the ripper teeth in their normal elevated position, with the rack bars out of engagement with the gears on the axle shaft. Figure 2 is a similar view of the ripper, showing the ripper teeth after they have entered the ground. Figure 3 is a top plan view of the ripper. And Figure 4 is a sectional view taken through the ripper on the line 4—4 of Figure 3, showing the position of an elevating rack just before its joint-breaking roller has engaged a respective gear on the axle shaft.

Referring to the accompanying drawings for a detailed description of the form of embodiment of my invention disclosed therein, the numerals 1, 1 designate the side members, and 2 the end members of a wheeled ripper frame. The side members 1, 1 are bent inwardly at their outer ends for connection by bolts 3 to the end member 2, and terminate at their front ends in inwardly inclined portions 4, 4 to which longitudinal frame members 5, 5 are secured. These latter members are formed at their ends with outwardly bent portions that are bolted to the end member 2. Two spaced center members 6, 6 parallel with the members 1, 1 and 5, 5 are bolted at their rear angle portions to the end member 2. U-shaped spacing elements 7 are bolted between the front ends of these longitudinal members.

Secured between the longitudinal members 1, 1 behind the center line of the machine, is a transverse member 8. Connected between the latter

and the end member 2 is a series of spaced tooth-supporting bars 9 between which ripper teeth 10 are bolted in staggered relation at their upper ends. Each ripper tooth is preferably constructed of flat high carbon steel for the purpose of adding to its strength. A pin 10^a is inserted in the top forward part of each ripper tooth, while a similar pin 10^b is secured in the bottom rearward part of the tooth. These pins straddle the bars 9 to relieve the bolts of the shearing strains to which they are subjected when the teeth are moved through the ground.

Secured to the rear middle portions of the longitudinal members 1, 1 are two oppositely disposed bearing blocks 11, 11 for a transverse shaft 12. Fixed to this shaft, one near each bearing block 11, are two axle arms 13, 13 that carry bearings for a transverse shaft 14 to which two road wheels 15, 15 are fixedly secured.

The elevating and dropping mechanism which I have provided for the ripper teeth 10 will now be described.

Bolted to the end member 2 of the ripper frame is an angle support 16 to which one end of a link 17 is secured by a pivot pin 18. Formed at the other end of this link is a sector plate 19 having a series of holes 20 near its curved edge. Pivoted to this plate by a pin 21 is one end of a link 22 secured at its other end by a pivot pin 23 to a crank arm 24 which is fixedly attached to the shaft 12.

The pivot pin 21 by which the link 22 is secured to the link 17, is below the center line between the pivots 18 and 23. For the purpose of breaking the joint between the links 17 and 22 to permit the ripper teeth 10 to descend by gravity into the ground, I have provided the following hand-operated means, although any other suitable device may be employed for this purpose if desired. The upper right corner portion of the sector portion 19 of the link 17 is formed with a boss 24 to receive a stub shaft 25. Secured to this shaft is a lever arm 26 and a foot member 27. While the link joint remains unbroken, as shown in Figures 1 and 4, the foot member 27 will rest upon the top edge of the link 22. However, when the lever arm 26 is pulled to the right, through a medium such as the cord 28, the engagement of the free end of the foot member 27 with the link 22 will elevate the sector portion 19 of the link 17 a sufficient distance to raise the pivot pin 21 above center, whereupon the machine frame will drop to force the ripper teeth 10 into the ground, as shown in Figure 2. The depth which the ripper teeth 10 are permitted to penetrate the

ground is controlled by the lever arm 26, the cord 28, the foot member 27 and the link 22.

ground will be determined by the insertion of a pin 20^a in a selected hole 20 in the sector portion 19 of the link 17.

In Figure 2, this pin having been inserted in 5 the second hole, will engage the lower edge of the link 22 to hold the ripper teeth 10 at the depth indicated in that figure.

For the purpose of raising the ripper frame from its earth moving position, I prefer the following means. Secured to the shaft 14, one near each wheel 15, are two gears 29, 29. Adapted 10 to be brought into engagement with each gear 29 is a curved rack bar 30 that is fixedly secured at its upper end to a transverse shaft 31 journaled in two upwardly inclined bracket arms 32, 32 respectively.

Also secured to the shaft 31 is an arm 33 formed in its free end with a hole to receive the hook end of a helical spring 34 whose other 20 end is secured to a rod 35. The lower end of this rod is adjustably secured to the cross member 8 to vary the tension of the spring. By means of the latter, the curved racks 30, 30 are held out of engagement with the gears 29, 29 respectively 25 when the ripper frame is in its elevated position. (See Figures 1 and 4.)

For the purpose of forcing the rack bars 30 into engagement with their respective gears 29, 29, I preferably employ the following link and lever means. Secured to one of the longitudinal 30 frame members 5 is a pivot block 36 to which a bell crank lever 37 is pivoted. The link end 38 of this lever is pivotally connected by a pin 39 between the upper ends of two parallel links 40, 40. These links terminate at their lower ends in slightly curved portions to receive between them a roller 41 free to turn on a pin 42. Just above the roller the links 40, 40 straddle, and are pivotally connected to the reduced lower end 40 of the adjacent rack bar 30 by a pin 43. Bridging the upper ends of the links 40, 40 is a stop member 44 to engage the link end 38 of the bell crank lever 37 when the links are straightened out, as shown in Figure 4.

45 When it is desired to raise the ripper teeth from the ground, the lever 37 is pulled forwardly by the operator through a medium such as the cable 45. This will cause the links 38 and 40 to straighten out, thus forcing the racks 30, 30 into engagement with their respective gears 29, 29 on the ground wheel shaft 14. The racks will then be turned in the direction of the arrow in Figure 4 to raise the ripper frame to the position shown in said figure, at which time the roller 42 will engage its respective gear 29 to break the joint between the links 38 and 40, whereupon the spring 34 will draw the free ends of the racks 30, 30 upwardly to the positions they occupy in Figures 1 and 2. The upward movement of the 60 ripper frame also forces the links 17 and 22 to the position they have in Figure 1.

It will now be seen that I have provided for earth moving devices such as rippers, scrapers and the like, a simple, quick and sturdy, automatic elevating mechanism for the earth engaging tool. Means having the same characteristics are also employed for throwing the earth moving device into the ground.

I do not wish to be limited to the details of 70 construction and arrangement herein shown and described, and any changes or modifications may be made therein within the scope of the subjoined claims.

Having described my invention, I claim:

75 1. In an earth moving device, a frame, an

earth moving tool attached to said frame, a ground wheel shaft mounted on the frame for vertical movement, a gear on said shaft, a swinging rack connected at one end to the frame, a link pivotally secured to the rack, a second link pivotally secured to the first link, the joint between the links being broken when the rack is out of engagement with the gear, and means for drawing the links into alignment with each other to force the rack into engagement with the gear. 80

2. In an earth moving device, a frame, an earth moving tool attached to said frame, a ground wheel shaft mounted on the frame for vertical movement, a gear secured to said shaft, a swinging rack connected at one end to the frame, a pair of pivotally connected links adapted, when in alignment, to force the rack into engagement with the gear whereby the frame may be raised by the ground wheel shaft, a spring for returning the rack to its normal position when the joint between said links is broken, and means carried by the lower end of the rack for engagement with said gear to break said joint after the rack reaches the limit of its travel in engagement with said gear. 90

3. In an earth moving device, a frame, an earth moving tool attached to said frame, a ground wheel shaft mounted on the frame for vertical movement, a gear secured to said shaft, a swinging rack connected at one end to the frame, a pair of pivotally connected links adapted, when in alignment, to force the rack into engagement with the gear whereby the frame may be raised by the ground wheel shaft, a spring for returning the rack to its normal position when the joint between said links is broken, one link being connected to the frame and the other link being pivotally connected to the free end of the swinging rack, and a roller on the last named link below its point of connection with the rack for engagement with said gear to break the joint between the links after the rack reaches the limit of its travel in engagement with said gear. 100

4. In an earth moving device, a frame, an earth moving tool attached to said frame, a transverse shaft journaled in said frame, a second shaft, ground wheels on the second shaft, arms fixedly secured to the first shaft and pivotally secured to the second shaft, a crank arm secured to the first shaft, a link pivotally secured to the said crank arm and a second link pivotally secured to the rear end of said frame, a pivot connecting the free ends of said links below their center line when the links are in alignment, and means for breaking the joint between said links to permit the earth moving tool to drop into the ground. 110

5. In an earth moving device, a frame, an earth moving tool attached to said frame, a transverse shaft journaled in said frame, a second shaft, ground wheels on the second shaft, arms fixedly secured to the first shaft and pivotally secured to the second shaft, a crank arm secured to the first shaft, a link pivotally secured to the said crank arm and a second link pivotally secured to the rear end of said frame, a pivot connecting the free ends of said links below their center line when the links are in alignment, a lever arm pivotally secured to the inner end of one link, and a member operated by the lever arm for engagement with the other link to break the joint between said links to permit the earth moving tool to drop into the ground. 120

6. In an earth moving device, a frame, an earth moving tool attached to said frame, a transverse shaft journaled in said frame, a second 130

link pivotally secured to the rear end of said frame, a pivot connecting the free ends of said links below their center line when the links are in alignment, a lever arm pivotally secured to the inner end of one link, and a member operated by the lever arm for engagement with the other link to break the joint between said links to permit the earth moving tool to drop into the ground. 140

shaft, ground wheels on the second shaft, arms fixedly secured to the first shaft and pivotally secured to the second shaft, a crank arm secured to the first shaft, a link pivotally secured to the said crank arm and a second link pivotally secured to the rear end of said frame, a pivot connecting the free ends of said links below their center line when the links are in alinement, means for breaking the joint between said links

to permit the earth moving tool to drop into the ground, a sector portion on the inner end of one link, said sector portion formed with a series of holes, and a pin insertable in a selected hole for engagement with the bottom edge of the other link to limit the downward movement of the earth moving tool when said joint is broken.
